DISPLAY STAND

William P. Schott, Rockville Centre, N. Y., assignor to Socony-Vacuum Oil Company, Incorporated, New York, N. Y., a corporation of New York

Application June 25, 1936, Serial No. 87,131

1 Claim. (Cl. 211—85)

This invention relates to a stand adapted for the displaying of goods in cans, or other packages, which are of such form and size that they may be placed upon horizontal racks.

5 The object of the invention is to produce a stand, for the purpose in question, which is of simple and inexpensive but strong construction, and particularly of a construction which permits the parts of the stand to be folded and laid compactly against each other for purposes of shipment and storage, and to be quickly and easily arranged and interlocked with each other when the stand is to be used.

To the foregoing ends, the stand is constructed with four legs, pivotally connected at the top in pairs and transversely braced by suitable tie bars, and with any convenient number of horizontal racks, which are supported upon the legs and so formed as to provide suitable support for rows 20 of cans or the like. The racks interlock with lugs or projections on the legs in such a manner that the legs are braced firmly in proper relative position so long as the racks are in place thereon.

The invention is more particularly described in connection with the embodiment thereof illustrated in the accompanying drawings, in which Fig. 1 is an end elevation of the stand, with the parts in position for use, portions being shown as broken away to reveal the construction more clearly; Fig. 2 is a side elevation of the stand, with a portion of one rack shown as broken away; Fig. 3 is an end elevation showing the legs when arranged in folded position; Fig. 4 is a perspective view of one of the racks; and Fig. 5 is a detail view showing a modified form of construction for supporting the racks and interlocking them with the legs.

In the illustrated embodiment of the invention the legs 10 are formed of angle iron and are pivoted together in pairs, at their upper ends, through the mediation of short links 11. The corresponding legs at each side of the stand are rigidly and permanently inter-connected by horizontal bars 12 fixed to the legs in any convenient manner as, for example, by spot welding.

As shown in the drawings the stand is provided with three horizontal racks, differing in dimensions but all similar in construction. Each rack comprises two parallel end bars 13 connected by two outer parallel side bars 14 and inner parallel bars 15. As shown in Fig. 4 the bars 13 and 14 are formed from a continuous strip of metal and the bars 15 attached rigidly to the bars 13 by welding or otherwise. The dimension of the rectangular space enclosed between the bars 15 and the bars 13 is such that these members surround and closely embrace the four legs at the level at which the rack is to be supported. For the purpose of supporting the racks the legs are

provided, as shown in Figs. 1 to 3 inclusive, with upwardly projecting lugs 16 on their faces, these lugs being conveniently, though not necessarily, formed by cutting and bending portions of the webs of the angle irons, as shown. When any 5 one of the racks is passed over the legs and engaged with the corresponding lugs the inter-engagement of the rack and the lugs not only supports the rack but also locks the legs in properly extended and braced position for use. On the other hand, when the stand is to be packed for 10 storage or shipment the legs and the cross bars 12 may be moved into compact parallel position, as shown in Fig. 3, and the several racks may be packed flat against the sides of the leg members. 15

The drawings show a number of larger and smaller cans 17 and 18 supported upon the stand in inclined position. The inner angle of each can, at the bottom, lies between the bars 14 and 15 of the rack, while the upper part of the can 20 rests against one of the cross bars 12, which are located at such heights as to be convenient for this purpose.

Fig. 5 shows a slightly modified form of construction in which, in place of the lugs 16 projecting from the faces of the legs and cooperating with the bars 15, there are short pins 19 projecting from the surfaces of the legs at the proper heights and cooperating with the bars 18 of the racks. These bars are notched, as shown, 30 to provide seats for the pins 19 and thus lock the legs in extended position.

I claim as my invention:

A display stand for cans or the like comprising, in combination, two pairs of legs, the legs 35 of each pair being pivotally connected at the top, horizontal cross members rigidly fixed to and interconnecting the corresponding legs of the two pairs, and a rack consisting of bars lying substantially in a common plane and rigidly connected together, the rack comprising four parallel bars, and two end bars respectively connecting the corresponding ends of the parallel bars, so that the end bars and the inner parallel bars constitute a substantially rectangular frame of 45 dimensions such that it may surround and embrace the legs when they are spread apart angularly, and projections on the legs, intermediate their ends and all in a common plane, engageable with said rectangular frame to support the 50 same on the legs in horizontal position, said projections and said frame being formed and arranged to be interlocked against relative horizontal movement by lowering the frame over the legs when the legs are sufficiently spread and to 55 prevent pivotal movement of the legs toward each other when the rack is in position thereon.

WILLIAM P. SCHOTT.
